INDICATING DIAL OR SIMILAR ARTICLE

Alfred K. George, Phoenix, Ariz.

Application April 10, 1953, Serial No. 24,452

Term of patent 14 years

(Cl. D52—1)

Fig. 1 is a perspective view showing the front, right side and bottom of an indicating dial or similar article embodying my new design.

Fig. 2 is a front elevation of the indicating dial shown in Fig. 1.

Fig. 3 is a right-hand side elevation of the indicating dial shown in Fig. 1.

Fig. 4 is a bottom view of the indicating dial shown in Fig. 1.

I claim:

The ornamental design for an indicating dial or similar article, as shown.
